UNITED STATES PATENT OFFICE

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT

DESIGN FOR A PUSH BAR FOR DOORS

Application filed January 10, 1930. Serial No. 34,093. Term of patent 14 years.

To all whom it may concern:

Be it known that I, ERNEST L. TEICH, a citizen of the United States, residing at New Britain, county of Hartford, State of Connecticut, have invented a new, original, and ornamental Design for Push Bars for Doors, of which the following is a specification, reference being had to the accompanying drawing, forming a part thereof,

The drawing is a perspective view of a push bar for doors showing my new design.

I claim:

The ornamental design for a push bar for doors as shown.

ERNEST L. TEICH.
